PROJECTION DISPLAY APPARATUS

Frank E. Weller, Bloomfield, N. J., assignor to
Trans-Lux Corporation, New York, N. Y., a corporation of Delaware

Application October 20, 1949, Serial No. 122,408

4 Claims. (Cl. 88—24)

1

This invention relates to a structurally and functionally improved display apparatus and especially an apparatus for use in the television industry.

It is an object of the invention to furnish a display apparatus which may be disposed in operative relationship to the camera or receiving unit employed in a television system and by means of which light images of imprinting, a time display, miniature or full-sized objects, etc., may be desirably received on the mosaic of the television camera to transmit reproductions of the matter so displayed.

A further object is that of furnishing an assembly of this type by means of which, for example, indicia on a narrow tape, or a broad web may be displayed in addition to the display of slides, miniature or full-sized objects, the face of a clock, etc., and regardless of whether the pictures or imprinting occur on a light-transparent member or an opaque surface; a single assembly of apparatus achieving the elected result at the will and under the control of the operator.

Another object is that of furnishing an apparatus which will include relatively few parts, each of individually simple and rugged design such parts being capable of ready assemblage and furnishing a unitary mechanism functioning over long periods of time with freedom from all difficulties.

With these and other objects in mind, reference is had to the attached sheets of drawings illustrating practical embodiments of the invention and in which:

Fig. 1 is a sectional plan view of an apparatus of this type;

Fig. 2 is a sectional side view of the same;

Fig. 3 is a transverse sectional view taken along the lines 3—3 and in the direction of the arrows as indicated in Fig. 2;

Fig. 4 is a sectional plan view of the rear portion of an apparatus embodying an alternative structure to that shown in the earlier figures;

Fig. 5 is a sectional side view taken along the lines 5—5 and in the direction of the arrows as indicated in Fig. 4;

Fig. 6 is a perspective view of a clock-mounting panel which may form a part of the assembly; and

Figs. 7, 8, and 9 are similar views showing respectively plates to be employed where the indicia on a narrow tape, broad web or series of slides is to be displayed.

Referring primarily to Figs. 1, 2, and 3, it will be seen that the numeral 10 indicates what might be termed the main casing of the device and which casing is conveniently of rectangular configuration. A removable or subsidiary casing portion

2

11 may be coupled with casing 10 in any desired manner, for example, by means of pin and hook connections as indicated at 12. Openings 13 are formed in the adjacent walls of the casings 10 and 11 and are aligned when the casings are coupled to each other. Casing 10 also mounts casing sections 14 and 15 which may be secured against displacement as indicated at 16. Sections 14 and 15 may form a subsidiary enclosure and the latter may have an opening 17 in its face. The several casing portions are preferably formed of metal.

The outer or front wall of casing 10 is formed with an opening across which a plate 18 is disposed. This plate conveniently supports or provides tubular guides 19 serving as mounts for lenses 20 and 21. The axes of these lens converge outwardly and towards a common point. Lights 22 may be disposed within casing 10 upon the base of the same and direct their rays towards the opening 13. A mirror 23 is adjustably mounted upon a bracket 24 conveniently supported by a casing portion 15 and so that light rays passing through the opening 17 may be reflected in line with the axis of lens 20. To provide a current of cooling air a blower 25 may be mounted within casing 10 to direct its blast past the front of light 22 and generally across the opening 13. The lower face of casing 10 may be formed with an opening 26 through which the heated air may be discharged.

Casing 11 may be shifted into position when it is desired to display objects by reflecting light rays. Such an object will be visible through the opening 13. It will be illuminated by the light rays emanating from the different bulbs 22 and converging upon the aperture. Frequently a series of such objects are to be sequentially displayed. To that end a shaft 27 may be rotatably mounted to turn on a vertical axis within casing 11. This shaft may support a turn table 28 having a series of compartments. The shaft may have attached to it a Geneva cross which is intermittently advanced by a pin and cam mechanism; this assembly having been indicated at 29.

The pin and cam are driven conveniently by a worm 30 mounted upon a shaft carrying a worm wheel driven by a worm 31. The latter is rotated by a motor 32. It is apparent that with the latter functioning the turn table will be intermittently advanced to sequentially display its compartments and any objects mounted therein. In the event that only a single object is to be displayed this may be conveniently framed within the apertures 13. Such an object may be a clock 33 mounted upon a suitable support 34.

Within casing sections 14 and 15, a guide 35 is disposed and which may have a width such

that it will properly cooperate with a narrow tape passing to a take-up reel 36. The guide 35 is disposed upon the opposite side of the casing from reel 36 and may receive the tape from, for example, an imprinting machine (not shown). Reel 36 is conveniently rotated by a spring belt 37 which passes around pulleys secured to the shaft of reel 36 and shaft 38 respectively. Shaft 38 is rotated by a drive element which is moved by a driving assembly 40 operated by a drive 39 mounted by shaft 41 extending from motor 42. Shaft 38 may also have secured to it a gear 43 meshing with a similar gear secured to a shaft 44. A belt and pulley connection 45 serves to connect this shaft with shaft 46 mounting a take-up reel 47, conveniently disposed adjacent the outer ends of casing 14. Disposed adjacent the opposite end of this casing is a guide assembly 48. The latter and the take-up reel 47 cooperate with a broad web and serve to guide and feed the same through the casing. That web, in common with the tape fed past guide 35 onto reel 36 may be transparent. It will ordinarily bear indicia imprinted in sequential lines extending parallel to the line of printing appearing upon the narrow tape.

The broad web has been indicated at 49 in Fig. 2 and the transparent, narrow tape has been indicated at 50 in Fig. 3. As also indicated in the drawings various auxiliary, guiding, aligning and tensioning mechanisms may be associated with the apparatus to assure that the webs or tapes are properly supported and moved. When the matter upon a narrow tape is to be displayed, then a masking plate 51 formed with a narrow aperture 52 as in Fig. 7 may be employed. When the indicia upon a broad web is to be displayed, the plate may take the form of a body 53 formed with a relatively wide aperture 54. These plates may also be provided with guiding extensions 55 and curved lip portions 56. Additionally, they may be furnished with positioning lugs 57 so as to be maintained against displacement with respect to the casing portions 14 and 15 and as shown substantially in line with the plane of juncture of these portions. One or the other of these plates may be thus disposed according to whether a web or a tape is being employed. If neither of these units are being employed, then a clock-mounting plate 58 having similar positioning lugs 57 may be disposed at the point indicated and include, for example, a transparent face 59 through which light rays may pass to silhouette the indicia upon its face as well as the outline of the clock hands traversing such face.

As is obvious, this clock-mounting plate 58, may be disposed as indicated in dotted lines in Fig. 2 in the event that simultaneous clock and tape-carried indicia images are to be displayed.

Above the station at which the masking plates 51 and 53 are disposed, a mounting 60 is pivotally supported as at 61 and carries a condenser lens assembly 62. The masking plate and this assembly will be optically aligned with the opening 17. Above the condenser assembly a source of illumination 63 is provided. This may conveniently embrace an incandescent bulb with which a reflector 64 is associated. As is apparent, due to the pivotal support of the mounting 60 the condenser lens assembly may be swung into and out of position to permit a removal and application of the various masking or mounting plates to the underlying supporting structure.

As shown in Fig. 9 a slide-supporting member may also be disposed in this position. In order to avoid unnecessary illustration this member has been illustrated in its simplest embodiment and

includes a main portion 65 formed with a framing aperture 66. Rail or guiding portions 67 may extend upwardly adjacent the edges of body 65. A detent in the nature of a raised part 68 may be formed in body 65. This will serve conveniently to provide a stop so that the user in pushing slides through the apparatus will know (when he encounters the increased resistance offered by the stop), that the slide is properly framed. To displace the slide so framed it will only be necessary to exert slight additional pressure so that it may override the detent portion. Accordingly a series of slides may be exhibited by manually traversing them over the surface of body 65. It is apparent that in accordance with conventional techniques a magazine and feeding mechanism (both not shown) might be employed in connection with the slide structure.

In the foregoing structures, excepting only 20 with respect to exhibits displayed and visible through aperture 13 indicia is silhouetted on transparent surfaces such as glass, cellophane, or paper tape, a similar web, etc. In certain instances, it might be desired to project the image 25 of indicia appearing upon opaque surfaces or bodies which are insufficiently translucent to employ light rays which pass through them to project images of the printed matter, pictures, etc. through the lens. If such projection is desired, then a structure such as is indicated in 30 Figs. 4 and 5 may be employed. In those views the numeral 69 indicates a casing section removably supported as, for example, at 12 and which is employed in lieu of casing section 11 as heretofore described. The latter is, of course, removed. Within the casing 69 there is disposed a supporting structure or guide 70 which will be disposed in line with aperture 13 when the parts are properly mounted. Passing over the display 35 station thus furnished is a strip 71 which may be considered to be formed of opaque material and have indicia upon its face arranged in the form of successive lines extending transversely with respect to its body. This web may be discharged from an imprinting machine (not shown) into the casing 69 and within the latter passes over suitable guides 72 and a feed roller 73 so that it traverses the station provided by the mounting 40 70. Feed roller 73 may be driven by a motor 74 and a reduction drive 75. A belt 76 conveniently extends between pulleys to transmit driving force from the roller 73 to a receiving reel 77 for the strip 71. It is thus apparent that the web 71 will move into casing 69 past the display station and be disposed upon reel 77.

In order to avoid unnecessary illustration, the structure shown in Figs. 4 and 5 has not been enlarged to include provision for the display of indicia extending longitudinally of a narrow tape. It is apparent that such display could be achieved by suitable modification of the parts and rearranging the direction of feed. Returning to Fig. 5, there has been shown at 78 a feed 45 controlling roller which bears against the web 71. This roller may be supported upon an arm 79 movably mounted to control the operation of a switch 80. While this is the only instance in which such a structure has been shown as part of the assembly, it will be understood that similar structures might be employed wherever necessary and be connected to control the functioning of motors such as 74 so that the latter will operate only when adequate web or tape material is entering the casings.

Also with a view of avoiding unnecessary illus-

tration, the present disclosures do not include showings of the obvious wiring diagrams which are embraced in the various units; nor do they show rheostats for controlling the speeds of the motors which feed the strips and tapes and operate the blower 25 and may moreover control the intensity of the light sources such as the lamps 22 and 63. Shutters which may interrupt the projection of the light beam have also not been included nor have the various diaphragms been illustrated which might be associated with the lens, openings such as 13 or 17, etc. to control the intensity of the beam. The desirability of such structures will be obvious to anyone skilled in the art.

With the foregoing in mind, it is apparent that in employing an apparatus such as has been shown generally in Figs. 1 to 3, an indicia-bearing broad web may be fed in operative relationship to the condenser assembly 62. With light 63 energized a suitable image will be projected through opening 17 onto the surface of mirror 23 and thence through lens 20. Optionally indicia upon a narrow tape or upon successive slides may be thus displayed as may also the face and hands of clock 59. If it is desired to superpose the latter image on the indicia display then the clock may be disposed as indicated in dot and dash lines within the aperture 13. Such display will, of course, require the energization of lamps 22. If, under these circumstances, lamp 63 continues to be energized, then the superposed images will be simultaneously projected to the mosaic of the camera arranged beyond such lenses. Obviously if light 63 is extinguished, then only the face of the clock appearing within aperture 13 will be visible.

The face of an opaque clock 32 may also be displayed within this aperture. With the removal of such an obstruction then the interior of casing 11 becomes visible through the opening and a single object or a number of objects which may either be stationary or movable will have their images reflected through the opening 13 and the lens 21. Again superposing of images may be resorted to. Also, as previously brought out, opaque indicia may be displayed through aperture 13 as shown in Figs. 4 and 5. It is apparent that by using the latter arrangement for example in conjunction with the structure which permits of the display of indicia upon a transparent mounting that a picture might be projected to the mosaic and this picture might be traversed by written indicia.

Thus, among others, the several objects of the invention as specifically afore noted are achieved. Obviously numerous changes in construction and rearrangement of the parts might be resorted to without departing from the spirit of the invention as defined by the claims.

I claim:

1. A display apparatus including in combination a main casing, a wall forming a part of said main casing, a removable casing also including a wall, said walls being formed with openings, quick detachable means for securing said casings against movements with respect to each other with said walls disposed adjacent each other and with the openings in alignment, display means within said removable casing and visible within said main casing through said openings, further display means extending into said main casing, means for directing light rays in illuminating relationship against both said display means and objective lens mounting means carried by said

main casing for directing light rays from both of said display means to points beyond said main casing.

5 2. A display apparatus including in combination a main casing, a wall forming a part of said main casing, a removable casing also including a wall, said walls being formed with openings, quick detachable means for securing said casings against movements with respect to each other with said walls disposed adjacent each other and with the openings in alignment, display means within said removable casing and visible within said main casing through said openings, further display means extending into said main casing, means mounted by said main casing for directing light rays in illuminating relationship against both of said display means and a pair of lens mounts supported by said main casing with their axes converging for directing light rays from both of said display means to a common point beyond said main casing.

10 15 3. A display apparatus including in combination a main casing formed with lens openings through which lens assemblies project, said casing being also formed with an opening to the rear of said lens openings, a source of illumination within said main casing to direct light rays through said latter opening, one of said lens openings being in optical alignment with said latter opening, a removable casing formed with an opening to also be aligned with said latter opening and detachable coupling means for securing said removable casing to said main casing.

20 25 30 35 40 45 50 4. A display apparatus including in combination a main casing formed with lens openings through which lens assemblies project, said main casing being also formed with an opening to the rear of said lens openings, a source of illumination within said main casing to direct light rays through said latter opening, one of said lens openings being in optical alignment with said latter opening, a removable casing formed with an opening to also be aligned with said latter opening, detachable coupling means for securing said removable casing to said main casing, an additional casing portion also formed with a projection opening directed into said main casing, a source of illumination within said additional casing portion, mechanism also within said additional casing portion for projecting light rays through the opening of the same and into said main casing and means for reflecting said latter rays in line with the axis of the second lens opening in the main casing which is to receive a lens assembly.

FRANK E. WELLER.
